CLAIM

The ornamental design for a fascia tissue fitness device with six treatment elements, as shown and described.

DESCRIPTION

FIG. 1 is a front perspective view of the fascia tissue fitness device with six treatment elements;

FIG. 2 is a front elevational view of the device of FIG. 1; FIG. 3 is a rear elevational view of the device of FIG. 1; FIG. 4 is a right-side elevational view of the device of FIG. 1;

FIG. 5 is a left-side elevational view of the device of FIG. 1;

FIG. 6 is a top view of the device of FIG. 1; and, FIG. 7 is a bottom view of the device of FIG. 1.

The broken lines depict portions of the handles that are unclaimed structure and form no part of the claimed design.

1 Claim, 4 Drawing Sheets
